Inventor
Marcus DeVoursney

United States Patent Office.

MARCUS DE VOURSNEY, OF NEWARK, NEW JERSEY.

Design No. 2,656, dated May 21, 1867.

DESIGN FOR A CARRIAGE-LAMP.

The Schedule referred to in these Letters Patent and making part of the same.

TO ALL WHOM IT MAY CONCERN:

Be it known that I, MARCUS DE VOURSNEY, of Newark, in the county of Essex, and State of New Jersey, have originated and designed a new Pattern for Carriage-Lamps, of which the following is a full, clear, and exact description, reference being had to the accompanying drawings, making part of this specification, of which—

Figure 1 is an elevation or front view of my design for carriage lamps complete, showing the peculiar construction of the same.

Figure 2 represents a vertical section on the plane indicated by the line *y y*, of fig. 1, showing the projection of the star reflector and a horizontal plate of glass extending but a part of the way between the lines *x x*.

Figure 3 is a plan or top view of the star reflector.

Similar letters of reference indicate like parts.

A indicates the metallic frame of the lamp; B the principal glass, moulded or cut, as shown in drawing; C represents the star made with points, D the ground of same, both of which combined produce the star reflector.

What I claim as my invention, and desire to secure by Letters Patent, is—

The herein-described design for carriage lamps, as shown and described.

MARCUS DE VOURSNEY.
